CLAIM

The ornamental design for a display screen with graphical user interface, as shown and described.

DESCRIPTION

FIG. 1 is a front view of a display screen with graphical user interface according to our new design; and FIG. 2 is a second embodiment thereof; and,

FIG. 3 is a third embodiment thereof.

The outermost broken lines in all figures illustrate the display screen. The remaining broken lines in FIG. 1 illustrate portions of the graphical user interface. None of the broken lines form part of the claimed design.
